[57] **CLAIM**

The ornamental design for a pull cap for a waterbed filler neck, as shown and described.

DESCRIPTION

FIG. 1 is an elevational view of a pull cap for a waterbed filler neck showing my new design with the lifting bails in raised position and the broken line structure being for purposes of illustration only;

FIG. 2 is a top perspective view of the cap with the bails in flattened condition;

FIG. 3 is a top plan view thereof;

FIG. 4 is an elevational view thereof taken 90° circumferentially from the position of FIG. 1;

FIG. 5 is a view like FIG. 1 with the bails in flattened condition; and

FIG. 6 is a bottom plan view of the cap in the condition of FIG. 2.
